UNITED STATES PATENT OFFICE.

RICHARD SPITTA, SEN., OF BRANDENBURG-ON-THE-HAVEL, PRUSSIA,
GERMANY.

APPARATUS FOR TANNING HIDES.

SPECIFICATION forming part of Letters Patent No. 308,003, dated November 11, 1884.

Application filed August 31, 1883. (No model.)

To all whom it may concern:

Be it known that I, RICHARD SPITTA, Sen., a subject of the King of Prussia, in the Empire of Germany, residing at the city of Brandenburg-on-the-Havel, in said Kingdom of Prussia, have invented certain new and useful Improvements in Apparatus for Tanning Hides and other purposes, of which the following is a specification.

10 This invention relates to vats for tanning, dyeing, or bleaching, in which a circulation or agitation of the tanning, dyeing, or bleaching liquor is maintained during the treatment of the hides or fabrics without removing them 15 from the vat.

The object of the invention is to secure a rapid and uniform change or agitation of the liquor throughout the vat.

Figure 1 is a vertical transverse section of 20 this apparatus in the form of a double vat. Fig. 2 is partly a plan with the cover removed and partly a horizontal section on line 2 2, Fig. 1, of a portion of a vat forming a part of this apparatus.

25 Similar letters of reference indicate corresponding parts in both figures.

A vat or tank, A, constructed of wood, stone, or other suitable material, is provided at one side with a partition, a, which divides the vat 30 into a tanning-compartment, D, and plunger-chamber E. The partition a is recessed at its upper and lower edges, or of less depth than the wall of the tank, whereby passages c c' are formed between the tanning-compartment and 35 the plunger-chamber at the top and bottom of the vat. Slats or bars h, provided with hooks from which hides are suspended, rest at their ends upon strips or ledges s, fastened to the walls of the tanning-compartment. A horizontally-elongated plunger, P, adapted to fit 40 and move within the plunger-chamber E, is reciprocated vertically therein by means of a rod, d, and a lever, f, to which said rod is connected. The lever f is pivoted at e to a suitable support or standard, g, and provided with a hook at its outer end adapted to receive a handle.

The tanning or other liquor is supplied to or removed from the vat by means of the pipe 50 m, the lower end of which discharges into the tanning-compartment, the upper end, m', being designed to be connected to the pump.

The operation is as follows: The hides being suspended in the tanning-compartment upon the hooks of the bar h, and the vat, including 55 the tanning-compartment and plunger-chamber, being filled with tanning-liquor, the movement of the lever f will reciprocate the elongated plunger e, whereby a uniform agitation or circulation of the liquor within the tank 60 will be effected, the downward stroke of the plunger forcing a uniform quantity of liquor through the lower elongated opening, e', in the partition a' into the tanning-compartment D throughout its entire length, and drawing an 65 equal quantity of liquor through the elongated opening e at the top of said partition into said plunger-chamber, the upward movement of the plunger producing a current in a direction the reverse of that just described. 70

It is preferable to construct the apparatus in the form of a double tank, as shown in the drawings, in which the interior of the tank is divided into two tanning-compartments, D D', by means of a central partition, a', said partition being provided with an opening, i, at the bottom of the tank, whereby communication between the compartments is established. This opening i may be closed by a slide, t, so that the compartments may be filled with the 80 liquor or emptied independently of each other. In this case one of the tanning-compartments, as D', may be provided with two sets of hooked bars arranged one above the other, whereby a larger number of hides of small size may be 85 suspended in the tank. In this case the tank is provided with an additional plunger-chamber, E', having a horizontally-elongated plunger, P', similar to the plunger P, heretofore described. The plunger P' may be connected 90 by the rod d' with the same lever or walking-beam f with which the plunger is connected. In such arrangement the plunger P moves downward while the plunger P' moves upward, and vice versa. In this manner a circulation is maintained within the separate 95 tanning-compartments, and if the slide t be opened there will also be a circulation between said compartments.

Having thus described my invention, I claim 100 as new and desire to secure by Letters Patent—

1. The combination, in an apparatus for tanning and other purposes, of a vat provided with a partition dividing said vat into a tan-

ning-compartment and a plunger-chamber, said partition having openings or passages at its top and bottom for the circulation of the liquor within the vat, and a horizontally-elongated vertically-reciprocating plunger adapted to fit and move within said plunger-chamber, substantially as described.

2. The combination, in an apparatus for tanning and other purposes, of a vat provided with two tanning-compartments separated by a central partition, and with two plunger-chambers separated from the tanning-compartments by means of partitions having openings at their upper and lower edges for the

circulation of the liquor within the vat, horizontally-elongated vertically-reciprocating plungers within said plunger-chambers, a walking-beam, a standard to which said walking-beam is pivoted, and rods connecting said walking-beam with said plungers, substantially as described.

In testimony whereof I have signed my name to this specification in the presence of two subscribing witnesses.

RICHARD SPITTA, SEN.
